UNITED STATES PATENT OFFICE.

GEORGE F. EGAN, OF JERSEY CITY, NEW JERSEY.

DISPLAY DEVICE.

Application filed April 9, 1926. Serial No. 100,986.

The present invention relates to improvements in display devices, and has for an object to provide a device for the display of price cards, tags and the like in which the device is constructed either for mounting upon a shelf or other support, or upon a counter, in a store window, or upon other flat support.

A further object of the present invention is to provide a holder for cards of various sizes and styles and to provide a convertible holder for a card which may be inverted or placed in either upright or inclined positions.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a front elevation of a display device constructed according to the invention and shown as upon a shelf partly broken away;

25 Figure 2 is a vertical section taken on the line 2—2, in Figure 1;

Figure 3 is a vertical section through a shelf and a rear view of the display device mounted thereon;

30 Figure 4 is a view similar to Figure 1 and with a price card shown in the device;

Figure 5 shows a section similar to Figure 2 with a price card in place;

35 Figure 6 is a rear view of a display device showing a slight modification;

Figure 7 is a front view of the display device shown in Figure 6;

Figure 8 is a section taken on the line 8—8 in Figure 7;

40 Figure 9 shows a view similar to Figure 8 illustrating the device as hanging on a beading of a shelf;

Figure 10 is a top plan view of the same;

Figure 11 is a front elevation of a device

45 involving a further modification;

Figure 12 is a vertical section taken through a shelf and showing the device of Figure 11 in edge view;

50 Figure 13 shows a device similar to Figure 1 with a large card resting in the bottom flange;

Figure 14 is a front elevation of a device such as shown in Figure 1 but in the inverted position;

55 Figure 15 is an edge view of the device shown in Figure 14 with a shelf in section;

Figure 16 is an edge view of a device such as shown in Figure 1 resting upon a flat support;

Figure 17 shows the same device in a different position on a flat support;

Figure 18 shows the device applied to an article, such as a shoe;

Figure 19 is a perspective view of a further modified form of device;

65 Figure 20 is a rear perspective view of the same;

Figure 21 is a perspective view of the device according to Figure 1 lying sidewise with a card therein;

70 Figure 22 is a perspective view of a further modified form;

Figures 23 and 24 are front and rear perspectives of further modifications;

Figure 25 is a front elevation of a further 75 modification;

Figure 26 is a rear elevation thereof;

Figure 27 is a plan view of the same;

Figure 28 is a vertical section taken on the line 28—28, in Figure 25;

80 Figure 29 is an edge view of the same as applied to a shelf shown in section; and

Figure 30 is an edge view of a further modification.

Referring for the present to Figures 1, 2 85 and 3, the device is made from a single piece of sheet metal bent and shaped to provide clamp arms or members 31 and 32, which are shown in Figures 1, 2 and 3 as engaging the upper and lower surfaces of a support 33, 90 such for instance as a shelf. These clamp members are bent into substantially parallel and spaced relation from the sheet metal body part or panel 34 having upper and lower flanges 35 and 36 which provide guideways 95 to receive a card when slid horizontally therein as indicated in Figure 4. The flanges are made integral with the sheet metal body and the upper flange is a continuation of the upper portion of the panel and is preferably of 100 reduced width as compared with the width of the panel so as to make it easier to slide a card into place. This flange is turned outwardly and downwardly to provide the guideway.

105 The lower flange 36 is cut or stamped out from the metal lying in the lower clamp member 32 adjoining the point of its connection with the lower edge of the panel 34 and this stamped out metal is bent downwardly, outwardly and upwardly to form the lower guide flange. This removal of the metal leaves the

lower clamp member 32 connected to the panel by the two end straps 37 and 38. These points of connection increase the flexibility of the hinging or resilient connection between the panel and the lower clamp member but being at the ends or lower corner portion of the structure, strength is secured and resistance to distortion maintained. The lower clamp member 32 is preferably arched intermediate its edges and it is shown as yieldably clamped against the lower portion of a shelf 33.

The upper clamp member 31 is stamped out from the panel and it is bent backwardly and when the device is placed on, for instance, a shelf 33, the clamp member 31 will lie upon the upper surface of the shelf 33.

Figure 4 shows a device with a price card 39 in place between the flanges 35 and 36. This card, in this instance, is of a height to be received slidably between the flanges, but may be much wider than the holder and this is permissible because of the lack of any stops or abutments for the card. The card is shown in Figure 5 in section as fitting tightly within the guideways, although freedom of movement is permitted in sliding horizontally.

In Figures 6 to 10, inclusive, the upper edge 40 of the cut out portion of the panel is rounded and as shown in Figure 10, the rear or free edge of the upper clamp member 31 is likewise rounded. The clamp members are the same in this form of the invention, but in addition a hanger strip 42 is shown as formed with the upper portion of the panel and as bent backwardly so that it may engage with a shelf indicated at 44, or with a bead 43 on a shelf. The hanger strip 42 and the upper flange 35 may be formed together by stamping the flange 35 out of the hanger strip 42 and bending the two in opposite directions.

Figures 11 and 12 show a similar form of device with similar parts indicated by the same reference numerals. These devices have additional side clips 45 and 46 shown as integral with the panel and bent forwardly and over toward the panel. The clips 45 and 46 are adapted to receive the lower reduced part 47 of a card having an enlarged head part 48 for the display of a legend or message. In this case the lower edge of the card is shown as fitted into the lower flange 36, but the card is much higher than the device and much too high to be received in the upper flange 35, so that it is placed outwardly of the upper flange and is retained at its side portions in the clips 45 and 46.

In Figure 13 a rectangular card 49 is shown of much greater size than the holding device. In this case the card may be received in a holder such as shown in Figure 1, the card simply resting in the lower flange 36.

In Figures 14 and 15 a holder, such as shown in Figures 1, 2 and 3, is illustrated, but in an inverted position upon a shelf 33.

In this instance the clamp arm or member 32 is shown as upon the top surface of the shelf, while the companion clamp member 31 is upon the lower side thereof.

Figure 16 shows a holder similar to that illustrated in Figures 1, 2 and 3, the holder being shown as resting upon a flat supporting surface. In the position shown in Figure 16 the panel of the holder is shown at an inclination to the vertical. The panel may, however, be vertical if desired. A large card 49, such as is shown in Figure 13, may be laid against the upper flange 35 and remain in position.

Figure 17 shows another position that the holder may assume on a flat supporting surface. Here the panel is shown as supported upon one edge and upon the clamp member 31. The panel is shown as resting in an inclined position and may receive any size card, the lower edge of the card being carried in the flange 35.

Figure 18 shows how the device may be applied to an article, such, for instance, as a shoe, for holding a price tag in connection therewith.

Figures 19 and 20 show the upper clamp member 31 and the lower flange 36 with rounded free edges. In this form no upper clamp member is used but side clips 50 and 51 are shown as provided to receive a card slid vertically downward into the holder. The device is also shown as provided with a hanging member 52 of narrow form having a substantially V-shaped slot 53 forming claws 54 and 55 which will enable a better grip to be had upon a supporting surface and the V-shaped slot may extend about the shank of a tack, nail, screw or other fastening, while the head may engage the claws 54 and 55 and thus hold the device in place.

Figure 21 shows a device as in Figure 1, except that the device is supported upon its side and the flanges 35 and 36 are disposed to receive a price card 56 vertically slid therein. In this position of the device a card of any height may be supported, and the card may be of the shape shown in Figure 11.

Figure 22 shows a device similar to Figures 19 and 20 except that in Figure 22 an upper flange 57 is stamped out and bent down from the panel of the device. The device shown in Figure 22 may be held in an inverted position on a shelf and a card may be held in place by the side clips 50 and 51 and supported by the flange 57. It is obvious that a card of the form illustrated in Figure 11 might be used in connection with the device shown in Figure 22.

In Figures 23 and 24 a device such as is shown in Figure 22 is illustrated but without the side clips 50 and 51.

Figures 25 to 29, inclusive, show a device also similar to that shown in Figure 22 with similar parts bearing the same reference sym-

bols. An additional supporting foot 58 is shown as provided in the forms illustrated in Figures 25 to 29. This supporting foot extends forwardly and in combination with the rear clamping member 32 provides a firm and strong base. The foot 58 is stamped and bent from the material of the lower clamp member 32 and the lower flange 36 is in turn stamped out of the foot 58 and bent upwardly.

19 Figure 30 is a view similar to Figure 1 but with the hanger member 52 of Figures 19 and 20 applied thereto.

It is obvious that various changes and modifications may be made in the details of construction and design of the above specifically described embodiment of this invention without departing from the spirit thereof.

I reserve the right to make all such changes and modifications as come within the scope of 20 the following claims.

What is claimed is:

1. A display device comprising a panel, clamp members extending rearwardly from the lower portion of the panel, a foot member 25 stamped from the material of the lower clamp member and bent forwardly of the plane of

the panel, a lower flange stamped from the material of the foot and bent upwardly therefrom, and an upper flange bent downwardly from the upper portion of the panel. 30

2. A display device comprising a panel, a member extending angularly to the panel, and adapted to rest on a support, a foot member stamped from the material of said first named member and bent to the opposite side 35 of the plane of the panel to also engage the support, and a card holding means stamped from the material of the foot member and bent upwardly therefrom.

3. A display device comprising a panel, a 40 claw bent rearwardly from the upper portion of the panel, a member bent from the lower portion of the panel and adapted to engage a supporting surface, a foot member stamped from the material of the last mentioned member and bent forwardly of the plane of the panel, and a card holding means stamped from the material of the foot and bent upwardly therefrom. 45

In testimony whereof I affix my signature.

GEORGE F. EGAN.
